(57) **CLAIM**

The ornamental design for a carburetor float bowl, as shown and described.

DESCRIPTION

FIG. 1 is a top, front, right side perspective view of a carburetor float bowl embodying my design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof; and,

FIG. 7 is a front elevational view thereof.

The broken lines show in the drawings represent unclaimed portions of the carburetor float bowl and form no part of the claimed design.
